UNITED STATES PATENT OFFICE.

ERNEST ALFRED LILLIE, OF LEICESTER, ENGLAND.

DESIGN FOR A FASTENING STUD OR BUTTON.

Application filed August 23, 1922. Serial No. 3,535. Term of patent 7 years.

To all whom it may concern:

Be it known that I, ERNEST ALFRED LILLIE, subject of the King of Great Britain, residing at Leicester, in the count of Leicester, England, have invented a new, original, and ornamental Design for a Fastening Stud or Button, of which the following is a specification, reference being had therein to the accompanying drawing, forming part thereof.

Figure 1 is a perspective view of a fastening stud or button showing my new design.

Figure 2 is a side view, and Figure 3 is a front view of the same.

I claim:

The ornamental design for a fastening stud or button as shown.

In testimony whereof I affix my signature.
ERNEST ALFRED LILLIE.
